DESIGN FOR A SAFETY SHIELD FOR TOOL GRINDERS OR SIMILAR ARTICLE

Herbert E. Tautz, Milwaukee, Wis., assignor to
The Delta Manufacturing Company, Milwaukee,
Wis., a corporation of Wisconsin

Application November 18, 1935, Serial No. 59,634

Term of patent 14 years

To all whom it may concern:

Be it known that I, Herbert E. Tautz, a citizen
of the United States, residing at Milwaukee, in
the county of Milwaukee and State of Wisconsin,
have invented a new, original, and ornamental
Design for a Safety Shield for Tool Grinders or
Similar Article, of which the following is a speci-
fication, reference being had to the accompany-
ing drawing, forming part thereof.

In the drawing,

Fig. 1 is a top view of a safety shield for tool
grinders, showing my new design;

Fig. 2 is a front elevation, and

Fig. 3 is a side elevation.

I claim:

The ornamental design for a safety shield for
tool grinders or similar article, as shown.

HERBERT E. TAUTZ.
